Paul L. Klein

Inventor
Carl Schneider

Paul L. Klein

UNITED STATES PATENT OFFICE.

CARL SCHNEIDER, OF NUTLEY, NEW JERSEY.

RECORD CONTAINER.

Application filed May 18, 1921. Serial No. 470,735.

To all whom it may concern:

Be it known that I, CARL SCHNEIDER, a citizen of the United States, and resident of 28 Woodland Ave., Nutley, in the county of Essex and State of New Jersey, have invented certain new and useful Improvements in Record Containers, of which the following is a specification.

This invention relates to record containers in general and particularly to the kind used in connection with dictaphones or similar apparatus.

At the present time various record containers are in use, which are either completely closed or have an arrangement whereby they are normally kept somewhat open and are subsequently closed when the record is inserted by pressing the divided portions together.

The disadvantage of record containers used heretofore is that the records are damaged while being taken from and particularly when being put into the receivers after they have been used for dictation or otherwise.

The record is usually slid into the receiver and since the latter is somewhat rough at the edge, the fine impressions made on the record are damaged when the record is not very carefully slipped into the receiver.

One of the objects of my invention is to provide an inexpensive, easily operable device for bodily receiving a record, while preventing the sliding in of the latter, thus insuring it against damages.

A further object of my invention is to provide such a device which will automatically close and remain normally in closed position.

A further object of my invention is to design this closing means in such a manner as to provide a leverage for manually opening the receiver when inserting a record.

Another object of my invention is to provide the opening end of the receiver with an inwardly turned edge for preventing the record, once inserted, from voluntarily or accidentally falling out of the receiver.

Another object of my invention is to provide resilient cushioning means within the receiver for preventing damage to the surface of the record.

From the foregoing it will be evident that the advantages of my device are manifold. Firstly, the user is compelled to completely

open my receiver since he is not able to put the record into it without first opening it, thereby eliminating damages to the surface of the record. The user is furthermore forced to open the container when he wishes to take out the record, thereby the sliding of the record is again eliminated.

In heretofore used containers where the record is slid into and out, special devices are provided protruding into the receiver for holding the record from within in order to prevent it from accidentally falling out. Such devices engage the inner surface of the record and when the latter is drawn out from the receiver, the inner surface of the record is naturally damaged.

Such damage makes a record untrue and badly affects the dictating operation and the shaving of the cylinder when in use, as upon the trueness of the inner record surface partly depends the proper receiving and transmitting of the sound.

When the record is secured in my device, the receiver automatically shuts and prevents the record from falling out.

The foregoing advantages will be more fully apparent from the following description and the accompanying drawings, forming part of this specification, in which:

Fig. 1 represents a longitudinal cross sectional view through a preferred form of my device, in open position.

Fig. 2 represents a cross sectional view through my device in closed position and secured within a record tray.

Fig. 3 is a detail end view of my device shown in preferred form.

Fig. 4 is a cross sectional view taken on line 4-4 of Fig. 3.

Fig. 5 is a cross sectional view taken on line 5-5 of Fig. 1.

Fig. 6 is a partial view of a modified form of my device.

Fig. 7 is an end view thereof.

Referring to the drawings, numerals 10 and 11 indicate semi-cylindrical members of my container, provided at one end with inwardly bent flanges 12 and 13 preferably covered with a resilient cushioning strip 14. At the inner surface of my device there is provided a plurality of semi-annular cushioning strips 15 and ring-formed end cushioning strips 16.

With the straight ends of the receiver members are associated semi-circular clos-

ing members 17 and 18 which are hingedly connected with each other as indicated at 19.

The closing members are provided with spring means 20 which causes them to normally close the two semi-cylindrical halves of my receiver, to which they are attached. The closing members are preferably provided with outwardly extending flanges 21 and 22. At the upper and lower portions of the flanges are provided recesses indicated at 21' and 22' to prevent the fingers resting against the flanges from slipping when my device is opened. The flanges 21 and 22 are so arranged as to extend beyond the pivotal point of the closing members, providing a leverage for facilitating the opening of my device.

When inserting or removing a record cylinder, indicated in dashed and dotted lines in Fig. 1, the container is opened to an angle of about 60°. At that point the abutting cutout edges 21'' and 22'', which are preferably bent inwards as shown in Figs. 3 and 4, come in contact with each other, thus preventing my device from opening further.

The construction of the closing members is preferably such as to provide a central opening 23 for receiving a pin 24 of a stand 25, illustrated in Fig. 2, by means of which the record and the receiver may be held in place.

In Figs. 6 and 7, there is a modified form of my closing member shown where the outer hinges 26 are made in the form of an eyelet and the spring member 20' comprises two wire springs passed through brackets 27 punched out from the material of the closing member.

The manner of attachment of the closing member to the semi-cylindrical receiver halves may be accomplished by rivets 28 as shown in Fig. 1, or by means of pressed-in prongs 29 as shown in Fig. 6 or in any other manner.

The construction of the closing member may be made in many different ways as long as the same desired results (that of causing the receiver halves to normally close) are accomplished. I therefore reserve for myself the right to make suitable changes and improvements within the scope of my invention to meet various conditions.

Having thus described my invention, I claim:

1. A new article of manufacture, a longitudinally divided cylinder having a flanged and hinged bottom and adapted to normally close, and means at the flanged bottom for facilitating opening the cylinder when desired.

2. A new article of manufacture, a longitudinally divided cylinder adapted to

be normally closed and having a flanged and hinged bottom, means at the flanged bottom for facilitating its being manually opened, and cushioning means provided within the cylinder.

3. A new article of manufacture, a longitudinally divided cylinder having a flanged and hinged bottom and a plurality of semi-annular cushioning means disposed within, means for normally closing the cylinder and means provided at the flanged bottom adapted to facilitate the cylinder being opened when desired.

4. A new article of manufacture, a pair of semi-cylindrical members having internally arranged semi-annular cushioning means and provided with semi-ring shaped, hinged bottoms, means associated with the bottom ends of said members for normally closing them and means for facilitating their being opened when desired.

5. A new article of manufacture, a pair of semi-cylindrical members having a plurality of internally arranged semi-annular cushioning means, a pair of semi-ring shaped, flanged end members adapted to permanently engage said semi-cylindrical members, said end members being hingedly connected with each other and adapted to force said semi-cylindrical members to normally close and provided with anti-slip means for facilitating opening of the latter when desired.

6. A new article of manufacture, a pair of semi-cylindrical members having a plurality of internally arranged semi-annular cushioning strips, one end of said semi-cylindrical members being open and provided with a substantially annular inwardly bent rim, and a spring actuated, hinged and flanged, semi-ring shaped closing and opening member associated with each of said semi-cylindrical members at their other end.

7. In a record receiver, the combination of a pair of semi-cylindrical members adapted to be normally closed and provided at one end with an inwardly bent edge, semi-annular cushioning means provided within the members, and over the said edge, a spring operated, hinged and flanged, semi-ring shaped closing member associated with each of said semi-cylindrical members at their other end, and so constructed as to provide sufficient leverage for opening said members when desired.

8. In a record receiver, as per claim 7, said closing member having a central opening for receiving anchoring means when in upright position.

Signed at New York, in the county of New York and State of New York, this 12th day of May, A. D. 1921.

CARL SCHNEIDER.
